Patented June 12, 1917.

Fig. R. 3453 Inventor: Carl G. G. Bergstrom
by: D. Bradbury Attorney.

UNITED STATES PATENT OFFICE.

CARL G. G. BERGSTROM, OF ST. PAUL, MINNESOTA, ASSIGNOR OF ONE-HALF TO GEORGE D. E. BERGSTROM, OF MINNEAPOLIS, MINNESOTA.

BAG-HOLDER.

1,230,060.

Specification of Letters Patent. Patented June 12, 1917.

Application filed April 24, 1916. Serial No. 93,071.

To all whom it may concern:

Be it known that I, CARL G. G. BERGSTROM, a citizen of the United States, residing at St. Paul, in the county of Ramsey 5 and State of Minnesota, have invented a new and useful Improvement in Bag-Holders, of which the following is a specification.

This invention relates to certain new and useful improvements in bag holders, and 10 more particularly to that class of devices which are especially designed to support receptacles, such as bags, sacks, and the like, in proper position to most conveniently receive articles to be placed therein.

15 An object of the invention is to provide a device for the purpose, comprising novel means about which the mouth of a collapsible receptacle of any size may be easily and quickly attached in open position for the 20 ready insertion of articles.

Another object is to provide a support for the receptacle supporting means which may be adjusted in height as found desirable and which may be positively locked in selected 25 position.

A further object is to provide such a support comprising sliding or other members having means under tension for normally retaining them in adjusted positions, but 30 which permits their rapid sliding movement with respect to one another to facilitate the filling of the bag.

Other and further objects and advantages 35 of the invention will be hereinafter set forth and the novel features thereof defined by the appended claims.

In the drawings:

Figure 1 is a side elevation of the invention partly in section and broken away, 40 showing a bag held in filling position thereby;

Fig. 2 is a plan of the invention, with some of the parts removed;

Fig. 3 is a partial end elevation looking 45 in the direction of arrow shown in Fig. 1; and

Fig. 4 is an enlarged section taken on the line X—X of Fig. 1.

Like numerals of reference refer to like 50 parts in the several figures of the drawing.

In the drawing, A represents a support or standard of any approved type comprising, as shown, an elongated bar 1 of metal or other rigid material, star-shaped in cross 55 section, and which is securely mounted on

a suitable base or platform B from which it extends vertically. Disposed for sliding movement upon the bar 1, is a comparatively short tubular member 2 having interior, longitudinal channel ways 3 within each of 60 which one of the radial projections 4 of the bar loosely fit as clearly indicated in Fig. 4. The tubular member 2 is composed of two sections 5 and 6, the upper extremity of the section 5 being enlarged and interiorly screw 65 threaded to coöperate with the threaded adjacent end of the section 6 as shown at 7 in Fig. 1. Near its enlarged portion, the section 5 is provided with a pair of spaced outstanding lugs 8 between which is pivoted one end of a dog 9, the other end of which has formed thereon a tooth 10 which engages with the waved serrations 11 formed on the outer edge of one of the radial projections 4 of the bar. By providing serrations of the 70 "wave" type, it will be understood that the dog 9 may freely ride along such surface in either direction as may become necessary to properly pack the produce placed in the bag 75 to be filled as will hereafter more fully and at large appear. At or near its lower end, the section 5 has secured thereto the ends of a U-shaped member 12 through the portion 13 of which is formed a threaded aperture to receive a bolt 15 having a short reduced inner end 16 about which a helical spring 17 is positioned, one extremity 18 of the spring resting against the end of the larger portion of the bolt and the other extremity 19 of the spring pressing against the 80 adjacent face of the dog to tensionally retain the same in engagement with the serrated surface 11 of the projection 4 of the bar and thus hold the member 2 in different 85 adjusted positions with respect to the bar. 90

On the upper face of one of the parallel arms of the U member 12 are a pair of spaced lugs 20 between which is pivoted a finger 21 adapted to be thrown into horizontal position so as to engage a face of the dog and to rest upon the face of the other of the parallel arms of the U member, a stop 22 being located thereon to firmly hold the finger against the face of the dog to positively lock the same against 100 accidental displacement. It is to be understood that the serrations 11 on the radial projection 4 of the bar are rounded or blunt so that the dog may ride thereover when a sufficient degree of manual effort 105 110

is brought to bear and the locking finger is released. Normally, however, the tension of the spring 17 is ample to hold the parts in selected position, the bolt 15 affording means for regulating the tension of this spring as may be desired.

Suitably secured about the section 6 of the tubular member 2 is a split collar 23 from which project arms 24 supporting at their free ends a horizontal iron jaw 25, the contour of which is preferably segmental, and the lower portion of which is provided with a plurality of spaced pointed teeth 26, the function of which will hereinafter appear.

Mounted for reciprocable movement upon the bar 1 is a yoke 27 having integral projections 28 suitably engaging the radial projections 4 on opposite sides of the bar 20 so as to guide the yoke in its movements. Extending outwardly from a face of the yoke are two lugs 29 between which is journaled the angle portion of a bell-crank comprising a pair of elongated diverging 25 arms 30 of equal length, the free end of each of which is provided with an aperture 31, through each of which extends a stud bolt 32 for fastening between the arms 30 a U shaped member 33 as shown in Fig. 2. 30 Pivots secured at one end by means of the stud bolts 32, on the opposite face of each of the arms 30 is a straight rod 33' extending in a substantially horizontal plane therefrom and which passes between flanges 34 formed on the opposite ends of 35 the jaw 25. It will also be noted that the free ends of the U-shape member 33 are bent outwardly and abut the rods 33' to further increase the rigidity of the parts. 40 At their free ends, the rods 33' carry an iron jaw 35 similar to the jaw 25, except that the convex faces of the two irons are oppositely disposed and that the teeth 36 of the jaw 35 project in an opposite direction from 45 that of the teeth 26 of the jaw 25. As shown, the jaw 35 is rigidly held upon the rods 33' by means of nuts 37.

The short arm 38 of the bell crank is provided with an aperture 39 by means of 50 which one end of a helical spring 40 is attached, the other end of the spring being secured through the medium of an eye-bolt 41 to a projection 42 projecting from the yoke 27. By this construction the tension 55 of the spring may be readily adjusted by turning the nut 43 with which the bolt is provided.

When it is desired to place a bag, represented by the reference character C, in filling position upon the device, the jaw 35 is forced inwardly, the mouth of the bag, or a portion thereof, secured upon the teeth 60 of the jaw 25, and when the jaw 35 is released, it will move outwardly due to the tension of the spring 40 and its teeth 36 will

engage a portion of the mouth of the bag in such manner as to hold it in distended position ready for filling.

Should it be desired to firmly pack the produce or articles in the bag, as when the same has been partially filled, this may be accomplished by grasping the rods 33' and the adjacent portion of the bag and reciprocating the tubular member and its attached parts rapidly up and down upon 75 the bar 1.

In order to evenly distribute and regulate the movements of the carriage mechanism for the movable bag supporting jaw 35, such mechanism including the rods 33', a 80 pair of evener rods 41' are provided, each of said rods being pivoted at one end as at 42 to one of the diverging arms 30 and at its other end between a pair of spaced lugs 43 carried by the stationary collar 23 85 by means of a threaded bolt 44, it being understood that each of said lugs is integrally secured upon the collar to opposite sides of the break therein so that the collar may be tightly held or loosened, as desired, 90 with respect to the member 2 through the medium of the bolt 44 as will be understood. The object of the evener rods 41' is to effect a respective up or down movement to the yoke 27 when the carriage 95 mechanism is moved in toward or away from the supporting standard 1 and in this way to effectually eliminate any binding tendency of the parts in their several movements. 100

Loosely mounted upon the member 2 above the stationary collar 23 is a second collar 45 having an arm 46 extending therefrom to the free end of which is secured by means of rivets 48 or other suitable means, 105 a guide chute 47 of any suitable configuration, but, as shown, it is of semi-circular shape and designed to facilitate the placing of the articles or produce within the bag. A plurality of spaced slots 14 one being 110 shown, are formed in the lower edge of the collar 45, and into any one of which a lug 49 formed on the member 2 is adapted to seat. When it is not deemed necessary to use the chute, it may be turned about on the 115 member 2 into inoperative position.

In accordance with the patent statutes, I have described the principles of operation of my invention, together with the apparatus which I now consider to represent the best 120 embodiment thereof, but I desire to have it understood that the construction shown is only illustrative, and that the invention can be carried out by other means and applied to uses other than those above set forth with- 125 in the scope of the following claims.

Having described my invention what I claim as new and desire to protect by Letters Patent is:

1. A device of the kind described compris- 130

ing a stand, an element rigidly mounted on said stand and adapted to engage a portion of the mouth of a bag, a stand, an element rigidly mounted on said stand and adapted to engage a portion of the mouth of a bag, 5 another element slidably mounted upon said first element and adapted to engage the mouth portion of said bag, a bell crank lever having its angle pivoted upon said stand and one arm movably connected to said slidably mounted element and a spring connected to the end of the other arm of said bell crank and to said stand and adapted to releasably urge the movable bag mouth engag- 10 ing element into outermost position and hold the mouth of the bag distended.

2. A device of the kind described, comprising, a base, a standard mounted on said base, a bag holding element rigidly carried 20 by said standard, a second bag holding element, carriage mechanism comprising a pair of spaced members slidably supported by said rigid element and carrying at their corresponding ends said second element, a member reciprocably disposed upon said standard, means connecting the free ends of said spaced members with said reciprocable member whereby movement of said second element is communicated to said reciprocable 25 member, and means co-operating with said aforesaid means for urging said second element away from said rigid element.

3. A device of the kind described, comprising, a base, a standard mounted on said base, a bag holding element rigidly carried 30

by said standard, a second bag holding element, carriage mechanism comprising a pair of spaced members slidably supported by 40 said rigid element and carrying at their corresponding ends said second element, a member reciprocably disposed upon said standard, means connecting the free ends of said spaced members with said reciprocable member whereby movement of said second element is communicated to said reciprocable member, and spring means co-operating with said aforesaid means for urging said second element away from said rigid element.

4. A device of the kind described, comprising, a base, a standard mounted on said base, a bag holding element rigidly carried by said standard, a second bag holding element, carriage mechanism comprising a pair of spaced members slidably supported by 50 said rigid element and carrying at their corresponding ends said second element, a member reciprocably disposed upon said standard, means connecting the free ends of said spaced members with said reciprocable member whereby movement of said second element is communicated to said reciprocable member, and means pivotally attached at one end to said standard and at the other end to said connecting means for eliminating 55 binding tendency of said parts during their respective movements.

In testimony whereof, I have signed my name to this specification.

CARL G. G. BERGSTROM.
